UNITED STATES PATENT OFFICE.

CHARLES W. GRIFFIN, OF NORA, NEBRASKA.

SHOCKER ATTACHMENT.

1,361,322.

Specification of Letters Patent.

Patented Dec. 7, 1920.

Application filed November 21, 1919. Serial No. 339,614.

To all whom it may concern:

Be it known that I, CHARLES W. GRIFFIN, a citizen of the United States, residing at Nora, in the county of Nuckolls and State 5 of Nebraska, have invented a new and useful Shocker Attachment, of which the following is a specification.

This invention relates to new and useful improvements in agricultural machines, and 10 more particularly to shocking machines, employed for receiving the bundle of grain from a binder, and positioning the same in a field, in the form of a shock.

The primary object of the invention is to 15 improve the shocker construction as shown by patent #1,222,796, by providing a delivering fork having a novel movement to cause the same to swing upwardly under the bundles discharged by the binder, to insure 20 against the bundle choking or otherwise clogging the machine due to the binder delivering bundles to the shocker more rapidly than the same can be removed by the shocker.

25 A further object of the invention is to provide a stationary table for receiving the bundles for temporarily supporting the same, after the bundles have left the binder.

With the foregoing and other objects in 30 view which will appear as the description proceeds, the invention resides in the combination and arrangement of parts and in the details of construction hereinafter described and claimed, it being understood 35 that changes in the precise embodiment of the invention herein disclosed, may be made within the scope of what is claimed, without departing from the spirit of the invention.

Referring to the drawing:—

40 Figure 1 illustrates a sectional view taken on line 1—1 of Fig. 3;

Fig. 2 illustrates a side elevational view of a conventional form of a shocker, showing the invention as applied.

45 Fig. 3 illustrates a plan view of the table and delivering means forming the subject matter of the present invention.

Having reference to the drawing in detail, the shocker is shown as supported by 50 the front or guiding wheels 8, and the rear wheels 6, the shocker including the usual frame 7, shocking cradle 5 and needle 9.

The shocker, as shown in the present instance, includes the body 7, the rear wheels 55 8 supporting the body 7, and the usual needle 9 supported adjacent one end of the

shocker, and adapted to move around a number of bundles, to loop a cord or other flexible means around the bundles to form a shock. 60

The device forming the subject matter of the present invention presents novel means for delivering the bundles of grain to the needle 9, and comprises the frame 10, including the side bars 11 and 12, connected 65 adjacent one end thereof by means of the end bar 13, the table 14 supported between the bars 11 and 12 extending from one end of the bars 11 and 12 and terminating at a point intermediate the lengths thereof. 70 This table 14, is provided with a plurality of parallel slots 15, which slots are disposed in suitable spaced relation with each other to receive the fingers of the delivering fork 16, which fork is designed to operate 75 through the slots 15, the same moving upwardly to carry grain bundles deposited on the table 14, to the tying needle 9.

The slots 15, as shown, extend from the inner edge of the table 14, and terminate at 80 a point substantially intermediate the length of the table 14, the slots being relatively wide to permit free movement of the fingers of the delivering fork 16 within the slots, so that the same may properly accomplish 85 the delivering result.

An operating crank 17 has its ends disposed in suitable bearings provided in the bars 11 and 12, the intermediate portion thereof being formed into the crank 18, 90 which crank 18 has connection with the delivering arm 16, by means of the apertured ears 19, forming a part of the delivering fork 16, the connection between the crank 18 and delivering fork 16 being such as to 95 permit of free pivotal movement of the delivering fork on the crank 18, when the delivering fork is being actuated.

This delivering fork includes a body portion 19', and spaced fingers 20, which as 100 before stated, operate within the parallel slots 15 and support the upwardly extending pins 21, disposed in spaced relation throughout the lengths of the fingers 20 and are provided for the purpose of engaging between the stalks of the grain forming the bundles to insure against the bundles falling laterally from the delivering fork when the same are being passed from the binder to the needle 9. 105

A forward crank arm 22, has its ends disposed in suitable openings, or bearings pro- 110

vided in the side bars 11 and 12, the intermediate portion thereof having pivotal connection with the arm 23 as at 24, the opposite end of the arm 23 being rigidly secured 5 to the body portion 19' of the delivering fork for reasons to be hereinafter more fully described. One end of the crank arm 22, is shown as bent at right angles to the main portion thereof as at 25, the extreme end 10 thereof extending inwardly toward the arm 11, as at 26, so that the same, on one of the movements of the delivering fork will contact with the under side of the bar 11, to cause the crank arm 22 to remain stationary, 15 for a predetermined period to provide a temporary stationary bearing for one end of the arms 23, to cause the delivering fork to swing to a position as indicated in dotted lines by Fig. 2 of the drawing.

20 The operating crank 17, receives motion from the wheel 6, through the endless chain 27 operating over the gear wheel 28 which is keyed or otherwise secured to the operating crank 17, so that movement of the gear wheel 25 28 causes a relative movement of the crank arm 17.

20 In operation bundles of grain are delivered from a binder not shown, on to the table 14. It follows that upon movement of 30 the delivering fork 16, from a position as indicated by Fig. 1 of the drawing, in the direction of the arrows in Fig. 2 of the drawing, to the position as indicated by dotted lines in Fig. 2 of the drawing, the bundles 35 are delivered to the cradle 5. Upon further movement of the delivering fork the lower end of the arm 23, takes a movement as indicated by the arrow at the lower end of the arm 23, which movement causes the delivering 40 fork to lie in a position in a horizontal plane under the table 14. The delivering fork upon further movement thereof swings upwardly under the table 14, the fingers 20 thereof passing through the slots 15, with 45 the result that bundles of grain delivered thereon are engaged by the fingers and move to a position to be operated on by the needle 9.

Having thus described the invention, what 50 is claimed is:

1. In a shocker, a table, a delivering fork associated with the table, said delivering fork adapted to remove material from the

table and deliver the same to the rear of the shocker.

2. In a shocker, a table, said table having a plurality of slots extending from one edge thereof, a delivering fork adapted to move upwardly through the slots for removing material deposited on the table and delivering the same to the rear of the shocker.

3. In a shocker having a needle forming a part thereof, a frame supported by the shocker, a table having connection with the frame, a delivering fork having a plurality of parallel fingers, said table having means to permit the fingers to pass upwardly through the table, and means on the fingers for contacting with materials deposited on the table for securing the material against displacement, and means for moving the delivering fork to a position adjacent the needle.

4. In a shocker having a needle forming a part thereof, a table having a plurality of 75 slots formed therein, a delivering fork including a plurality of fingers operating through the slots, spaced pins formed on each of the fingers, said pins adapted to contact with material supported on the table 80 upon movement of the fingers through the slots, and means for causing the delivering fork to move to a position adjacent the needle.

5. In a shocker having a needle forming 85 a part thereof, a table, a delivering fork associated with the table, and adapted to receive material therefrom, a pair of crank arms operating in spaced relation with each other and having connection with the delivering fork, means having connection with one of the crank arms for causing rotary movement thereof, means forming a part of the adjacent crank arm for causing the last mentioned crank arm to be stopped during 90 a portion of its movement for causing the delivering fork to swing upwardly through the table.

In testimony that I claim the foregoing as my own, I have hereto affixed my signature 100 in the presence of two witnesses.

CHARLES W. GRIFFIN.
